UNITED STATES PATENT OFFICE.

CHRISTIAN E. LIEBENBERG, OF CHESTER, PENNSYLVANIA.

BELT-SHIFTER.

1,301,464.

Specification of Letters Patent. Patented Apr. 22, 1919.

Application filed August 27, 1918. Serial No. 251,678.

To all whom it may concern:

Be it known that I, CHRISTIAN E. LIEBENBERG, a British subject of South Africa, residing at Chester, in the county of Delaware 5 and State of Pennsylvania, have invented certain new and useful Improvements in Belt-Shifters, of which the following is a specification.

My invention relates to new and useful improvements in a belt shifter and has for its principal object the construction of a device of this character which is simple and inexpensive in construction and particularly adapted for use with stepped pulleys although it might equally as well be used with pulleys of other construction.

A further object of the invention is the provision of means for securing the shifter in its various adjusted positions whereby 20 the belt will not be accidentally shifted.

Another object is the provision of means whereby the belt will always be shifted from a larger to a smaller step first.

With these and other objects in view my 25 invention consists in the novel detail of construction and arrangement of parts which will be more clearly understood from the following specification and drawings in which:—

30 Figure 1 is a perspective.

Fig. 2 a transverse vertical section of the line 2—2 of Fig. 1, and

Fig. 3 a longitudinal section through the 35 slidable shifter casing.

In the drawings the numeral 1 indicates the machine head stock having the stepped pulley 2 rotatably mounted therein. The countershaft is indicated at 3 and has the stepped pulley 4 secured thereto in any well 40 known manner. The machine head stock, the shaft and stepped pulleys form no part of my invention as each may be of any conventional type.

Vertically spaced tracks 5 and 6 may be 45 secured to the machine or counter-shaft hanger in any desired manner and these tracks are preferably formed of flat strips as more particularly illustrated in Fig. 1 of the drawings. Longitudinally spaced notches 7 50 are formed in one end of each of the tracks 5 and 6 for the purpose which will be presently described.

A casing 8 is slidably mounted upon the track 5 and is provided in one end with a 55 central opening and in the opposite end with an opening which is offset to provide a pro-

jection indicated at 9 which is adapted to normally rest in one of the notches 7. The casing is provided along one edge with the longitudinally spaced openings 10, for the 60 purpose as will be presently described, and a flat spring 11 is secured in the casing adjacent one end, and normally bears against one edge of the track 5 as is more particularly shown in Fig. 3 of the drawings. It will be 65 understood that the track 5 passes through the openings in the ends of the casing as shown. The openings 10 are formed in that edge of the casing adjacent the edge of the track without the notches. Longitudinally 70 spaced pins or projections 12 extend from one edge of the casing and the object of the pins or projections will be presently described.

A casing 13, similar to the casing 8, is 75 slideable on the track 6 and is provided along one longitudinal edge with openings 14 corresponding with the openings 10. This casing 13 is also provided with the end openings the same as the casing 8 and is also provided on the interior with a spring, not shown, similar to the spring 11. Pins or 80 projections 15 are formed on the edge of the casing 13 and extend in a direction opposite to the pins or projections on the casing 8. 85

A belt 16 encircles the pulleys 2 and 4, as shown, and this belt is adapted to operate between the pins or projections 12 and the pins or projections 15 formed on the respective casings 8 and 13. These pins or projections form a guide for the belt as well as for shifting the belt as will be later described.

A vertical rod 17 is rotatably mounted in suitable bearings not shown and is provided 95 intermediate its ends with a wheel 18 as shown in Fig. 1 of the drawings. Arms 19 and 20 are secured upon the rod 17, the arm 19 being adjacent the casing 8 and the arm 20 adjacent the casing 13. The arms 19 and 100 20 are set at the angle shown whereby they will extend approximately at right angles with respect to one another and in their initial position will be in the position illustrated in Fig. 1 of the drawings. The vertical rod 17 is spaced from the edge of the casings and the arms 19 and 20 are of such length as to engage in the notches or openings 10 and 14 when said rod 17 is rotated.

From the above detailed description it is 110 thought that the construction and operation of my improvements will be clearly under-

stood. Assuming the several parts to be in the position illustrated in Fig. 1 of the drawings and it is desired to shift the belt the wheel 18 will be grasped by the hand 5 and turned so as to rotate the rod 17. This will bring the arm 19 into contact with the casing 8 adjacent the first opening 10, or that opening adjacent the end of the casing, and will force the casing against the 10 tension of the spring 11 and thereby raise the extension 9 from engagement with the notch 7. The continual rotation of the rod will bring the end of the arm into the opening and will slide the casing along the track 15 5. This will shift the lower end of the belt from the larger step of the pulley 2 to the next step and the continuous rotation of the rod will then bring the arm 20 into engagement with the edge of the casing 13. The 20 operation will be the same as described for the casing 8 and after the casing has been shifted so that the projections will disengage from the notch the casing will be slid thereby shifting the upper end of the belt 25 from the smaller step to the next larger step. After the casing has been adjusted it will be understood that the projection 9 will engage the next notch 7 thereby locking or securing the casings in adjusted position. When it is desired to shift the belt in a reverse direction, it will be understood that the casing 13 will be first slid and then the casing 8. In shifting the belt will always be first shifted from a larger to a 30 smaller step. When the rod 17 has been rotated to a sufficient distance the spring 11 will always draw the projections or extensions 9 into one of the notches. As previously stated the studs or extensions 12 and 35 15 on the casings 8 and 13 will straddle the belt to act not only as a guide but as means for shifting the belt.

The foregoing description and the drawings have reference to what may be considered the preferred, or approved form of my invention. It is to be understood that I may make such changes in construction and arrangement and combination of parts, materials, dimensions, et cetera, as may prove expedient and falls within the scope of the 45 50 appended claims.

Having fully described my invention what I claim as new and desire to secure by Letters Patent is:—

55 1. A belt shifter comprising a track having notches in one edge thereof, a casing 60 slidable upon the track, projections carried by the casing for engaging the belt, a projection formed on the casing for engaging the notches of the track, and means for sliding the casing.

2. A belt shifter comprising a track hav-

ing notches on one edge thereof, a casing 65 slidable upon the track, a projection carried by the casing and adapted to engage the notches in the track, a spring secured in the casing and engaging the track, projections formed on the casing and adapted to engage the belt, and means for sliding the casing.

3. A belt shifter comprising a track, a 70 casing slidable upon the track and provided with notches in one edge, thereof, a spring secured in the casing and engaging the track, projections on the casing adapted to engage the sides of the belt, a vertical 75 rod rotatably mounted adjacent the casing, and an arm secured to the rod and adapted to engage in the notches in the casing for sliding the casing.

4. A belt shifter comprising vertically 80 spaced horizontal tracks having notches formed in one edge thereof, casings slidable upon the tracks and provided with notches in one edge thereof, projections formed on the casings and engaging the sides of the 85 belt, a projection formed adjacent one end of each casing and adapted to engage the notches in the edge of the track, a spring secured in the casing and adapted to engage the track, a vertical rod rotatably mounted 90 adjacent the tracks, vertically spaced arms secured to the rod and adapted to engage the notches in the casings, said arms being at right angles with respect to one another, and a wheel secured to the rod. 95

5. A belt shifter comprising a track, a casing slidable upon the track, said casing having a central opening in one end and an offset opening in the opposite end, a spring carried by the casing and adapted to engage 100 the track for holding one edge of the offset opening in contact with the edge of the track, projections carried by the casing and adapted to engage the belt, and means for sliding the casing. 105

6. A belt shifter comprising a track having notches in one edge, a casing slidable upon the track, said casing having a central opening in one end and an offset opening in the opposite end, a projection formed on one 110 end of the offset opening, a spring carried by the casing and adapted to engage the track for holding the projection on the end of the offset opening in one of the notches in the edge of the track, projections carried 115 by the casing and adapted to engage the belt, and means for sliding the casing.

In testimony whereof I affix my signature in presence of two witnesses.

CHRISTIAN E. LIEBENBERG.
